UNITED STATES PATENT OFFICE.

WILLIAM A. HOLDREN, OF SABETHA, KANSAS.

STREET-SWEEPING MACHINE.

1,236,841.

Specification of Letters Patent. Patented Aug. 14, 1917.

Application filed December 8, 1915. Serial No. 65,844.

To all whom it may concern:

Be it known that I, WILLIAM A. HOLDREN, a citizen of the United States, residing at Sabetha, in the county of Nemaha and State 5 of Kansas, have invented new and useful Improvements in Street-Sweeping Machines, of which the following is a specification.

This invention relates to street sweeping machines of that general type or class which 10 are provided with a revolving brush, and it has for its object to produce a machine of simple and improved construction which will be practically dust-proof in operation, thereby dispensing with one of the most serious 15 objections to the use of street sweeping machines of ordinary construction.

A further object of the invention is to simplify and improve the manner of mounting and driving the revolving brush, of adjusting 20 the same with respect to the ground, and of moving the said brush to and from operative position.

A further object of the invention is to simplify and improve the dust carrying and 25 receiving means and the mechanism for dumping the contents of the dirt receptacle.

With these and other ends in view which will readily appear as the nature of the invention is better understood, the same consists 30 in the improved construction and novel arrangement and combination of parts which will be hereinafter fully described and particularly pointed out in the claim.

In the accompanying drawings has been 35 illustrated a simple and preferred form of the invention, it being, however, understood that no limitation is necessarily made to the precise structural details therein exhibited, but that changes, alterations and modifications 40 within the scope of the claim may be resorted to when desired.

In the drawings,—

Figure 1 is a view in side elevation of the improved machine, the greater part of the 45 housing or dust protector having been removed from the near side of the machine.

Fig. 2 is a side elevation showing the opposite side of the machine from which the greater part of the covering has been removed 50 from the near side.

Fig. 3 is a top plan view with the covering partly removed.

Fig. 4 is a longitudinal vertical sectional view taken on the line 4—4 in Fig. 3.

55 Fig. 5 is a transverse sectional view taken on the line 5—5 in Fig. 1.

Fig. 6 is a rear elevation.

Fig. 7 is a transverse sectional view taken on the line 7—7 in Fig. 2.

Corresponding parts in the several figures 60 are denoted by like characters of reference.

The frame A of the improved machine, which is of skeleton construction, is supported near its rear end by the main axle 15 having the ground wheels 16, 17 which are 65 loosely mounted with respect to the axle, but which are utilized to rotate the axle when the machine is moved forwardly through the medium of clutch devices 18 of well known construction, said clutch devices 70 being conventionally indicated. Mounted on the ground wheel 16 for rotation therewith is a sprocket wheel 19, and associated with the ground wheel 17 for rotation therewith is a spur wheel 20. The forward part of the 75 frame is supported on a steering truck 21 arranged to swing about the axis of a king bolt 22 which is connected with the frame by a brace 23, said steering truck being equipped with a tongue 24 and with low ground wheels 80 25 which are capable of swinging beneath arched portions 26 of the frame.

The side portions of the frame are provided at the rear ends thereof with inclined guides 27, said guides being inclined downwardly and forwardly to support the slides 28 affording bearings for a shaft 29 carrying a cylindrical brush 30, the tufts of which are preferably made of wire or other sufficiently durable resilient material. The brush 90 carrying shaft 29 is equipped with a pinion 31 which, when the brush is at or near the downward limit of its movement and in engagement with the ground, will mesh with the spur wheel 20, whereby the brush will 95 be rotated at a speed which will be governed by the proportionate sizes of the spur wheel and the pinion. The slides 28 are connected by links 32 with arms 33 extending from a lever 34 which is fulcrumed at 35 100 on top of the frame, and which extends forwardly within reach of the operator whose seat 36 is mounted near the forward end of the frame. A rack bar 37 is provided with which the lever 34 may be engaged for the purpose of retaining it and the slides carrying the rotary brush in adjusted position.

The main frame A supports a pair of forwardly and upwardly inclined elevator frames, namely, the top frame 38 and the 110 bottom frame 39, said elevator frames leading from within a short distance of the ro-

tary brush to the top of the dirt receptacle 40. The top and bottom elevator frames are provided near their lower ends with roller shafts 41, 42 and near their upper ends with roller shafts 43, 44 over which endless conveyers 45, 46 are trained, said conveyers being constructed of flexible, preferably textile, material and provided with transverse slats 47, 48. Mounted for rotation on the shaft 44 at the upper end of the bottom elevator is a sprocket wheel 49 which is connected by a chain 50 with the sprocket wheel 19 on the ground wheel 16. Slidably mounted on the shaft 44 and connected for rotation therewith by a key or spline 51 is a spur wheel 52 having laterally extending pins 53 adapted to engage recesses 54 in the face of the sprocket wheel 49, said inter-engaging ends and recesses constituting a clutch device whereby the sprocket wheel may be locked upon the shaft for rotation therewith, thus causing said shaft to be driven from the ground wheel 16 when the pins 53 are in engagement with the recesses 54, and causing the sprocket wheel to rotate idly when the engagement is interrupted. This may be effected by means of a shipping lever 55 fulcrumed on a bracket 56 connected with the frame structure and by means of which the spur wheel 32 may be moved longitudinally of the shaft 44. A rack bar 57 is provided with which the lever 55 may be placed in engagement for the purpose of securing said lever and the ratchet wheel in adjusted position. The shaft 43 at the other end of the top elevator is provided with a spur wheel 58 meshing with the spur wheel 52 on the shaft 44 of the bottom elevator from which motion in the proper direction will thus be transmitted to the top elevator. It is obvious that the spur wheel 58 is to be sufficiently wide to enable it to remain in mesh with the spur wheel 52 when the latter is moved longitudinally of the shaft 44 for the purpose of placing the elevators in or out of gear through the medium of the clutch mechanism hereinbefore described.

The dirt receptacle consists of a box or 50 casing, the lower end of which is provided with trap doors 59 which may be retained in closed or obstructing position by means of chains 60 that are suitably guided over guide wheels 61 on a shaft 62, said chains being terminally connected with a drum 63 operable by means of a crank 64, said drum being also equipped with a ratchet wheel 65 engaged by a pawl or dog 66 which, by preventing rotation of the drum, will serve to 60 maintain the trap doors in closed position. By releasing the pawl, the weight of the contents of the box will cause the trap doors to swing open, the chains being unwound from the drum. The closing of the trap doors after discharging the contents of the

dirt receptacle may be effected by properly manipulating the drum handle or crank.

The machine, excepting the transporting wheels, the exterior gearing, the extreme forward part of the frame on which the seat is supported and the hand levers 34 and 55, is housed in a tightly fitting casing 67 of sheet metal which extends within a short distance of the ground. Connected with the lower edge of the housing 67 is a resilient 70 strip 68 of leather or other flexible wear resisting material which is intended to extend so nearly toward the surface of the ground as to practically prevent the escape of dust raised by the operation of the brush. 75 The said resilient strip may, if desired, actually contact with the surface of the ground, inasmuch as its flexibility will cause it to yield to any obstructions that may be encountered. It will be found desirable to 80 connect the strip 68 adjustably with the housing 67 by means of fastening means, such as bolts 69, engaging slots 70 in the strip which may thus be raised or lowered, as may be desired, and which may also be 85 adjusted to compensate for wear.

For the purpose of guiding the sweepings from the rotary brush to the lower elevator a scoop or pan 71 is provided, said scoop being hingedly connected at 72 with the lower elevator frame, and springs being provided, as seen at 73, whereby the free edge of the scoop is forced in a groundward direction. The receiving edge of the scoop will thus be maintained in ground engaging 95 position, but it will be free to rise and to ride over any obstructions that may be encountered.

From the foregoing description, taken in connection with the drawings hereto annexed, the operation and advantages of this invention will be readily understood. The rotary brush will sweep the dirt over the scoop and onto the lower elevator, the dirt being carried by said elevator to the receptacle. The top elevator will coöperate with the lower elevator to carry the dirt, and it will also serve to confine the dust and dirt and prevent its being scattered. The housing surrounding the frame of the machine 105 will practically prevent the dust raised by the brush from being scattered, thereby overcoming one of the serious objections to the use of street sweeping machines in general. The construction of the improved machine is simple, and it has been found to be 110 thoroughly efficient for the purposes for which it is provided.

Having thus described the invention, what is claimed as new, is:—

In a street sweeping machine, a wheel supported frame, a revolving brush, an upwardly and forwardly inclined bottom elevator receiving the sweepings from the brush, shafts over which said elevator is 120

trained, a sprocket wheel mounted idly on one of the shafts and driven by a chain from one of the supporting wheels, a spur wheel slidably mounted on the shaft adjacent to the sprocket wheel and having clutch means adapted to engage the same, a top elevator juxtaposed to the bottom elevator and coöperating therewith to carry the sweepings, shafts over which said top elevator is trained, and a spur wheel on one of said shafts meshing with the spur wheel

on one of the shafts of the bottom elevator and of a width sufficiently exceeding the width of the last mentioned spur wheel to cause it to remain in mesh therewith in various positions thereof. 15

In testimony whereof I affix my signature in presence of two witnesses.

WILLIAM A. HOLDREN.
